HEEL BONE TRACTION SPLINT

Lloyd E. Hansberry, San Francisco, Calif.

Application February 4, 1946, Serial No. 645,343

3 Claims. (Cl. 128—85)

1

This invention relates to heel bone traction splints and has for its object the provision of a splint of this character designed to be incorporated in the leg cast of a patient with no portion thereof extending below the heel of the patient and so constructed that compensation can be made for any misalignment of the hole drilled in the heel for the reception of the heel bone pin.

The invention possesses other advantageous features, some of which with the foregoing will be set forth at length in the following description where that form of the invention which has been selected for illustration in the drawing accompanying and forming a part of the present specification is outlined in full. In said drawing one form of the invention is shown, but it is to be understood that it is not limited to such form, since the invention as set forth in the claims may be embodied in a plurality of forms.

Fig. 1 is a perspective view of a heel bone traction splint embodying the objects of my invention.

Fig. 2 is a vertical midsection taken through one of the springloaded longitudinally adjustable heel bone pin carriers shown in Fig. 1.

The traction splint shown in these two figures includes a pair of opposed and identical metal straps 1 and 2 fashioned to conform generally to the contour of the lower leg. Securing the straps 1 and 2 in laterally spaced relation with respect to each other are a pair of resilient outwardly arched connecting members 3 and 4 designed to straddle the shin bone of the lower leg and preferably made of spring steel. Pivoted to the lower end of each of the straps 1 and 2 by a bolt 5 is a strap extension 6 formed at its lower end with an elongated open ended slot 7. Threaded to each of the bolts 5 is a nut 8 by which the strap extension can be locked to its associated strap in any selected angular position with respect thereto. Formed integral with each of the extensions 6 is an outwardly extending bracket 9, and secured to each of these brackets is a guide rod 11 extending downwardly in parallelism with its associated strap extension 6. Telescopically or slideably disposed over each of the guide rods 11 is a sleeve 12, formed at its lower end with a head 13 provided with wrench faces 14. Surrounding each of the guide rods 11 and its associated sleeve 12 and disposed between the bracket 9 and the upper face of the head 13 is a spring 15 arranged to urge the sleeve 12 and its head 13 downwardly. Threaded to each of the heads 13 coaxially with the sleeve 12 is an adjusting screw 16, the head 17 of which is formed with a longitudinal slot 18 in alignment with the slots 7 for the reception of a heel bone pin 19. Threaded to the head 17 of each of the adjusting screws 16 is a transverse set screw 20 formed with a tapered end 21 and by which the heel bone pin 19 can

2

be secured to the adjusting screw 16. Indicated on the outer face of each of the straps 6 is a pressure scale 22 preferably expressed in units of pounds. The zero line of the scale 22 should be so positioned that it is in alignment with the upper face 23 of the head 13 when the face 23 is just in engagement with the spring 15 and the spring 15 is in its relaxed condition.

In the use of a device of the character above described a transverse hole is first drilled in the heel bone of the patient for the reception of the heel bone pin 19. The straps 1 and 2 are then embedded in a cast formed about the lower leg, with the connecting members 3 and 4 disposed over the shin bone with the strap extensions 6 protruding from the cast and with the slots 7 of the strap extensions straddling the heel bone pin 19. The strap extensions 6 are then locked to the straps 1 and 2 by the nuts 8. This having been done, the heads 13 are advanced upwardly or downwardly with respect to the screws 16 so that the upper faces 23 of each of the heads 13 are in transverse alignment with the zero line of the scale 22 and the closed ends of the slots 18 are just in contact with the heel bone pin 19. As so set there is no pressure on the heel bone pin. The heads 13 can then be rotated to run the screws 16 downwardly so as to produce any desired pressure on the heel bone pin 19.

From the above description it will be seen that I have provided an articulated heel bone traction splint readily adjustable to compensate for any inaccuracies in drilling the hole for the heel bone splint and no part of which extends below the patient's foot.

I claim:

1. A traction splint of the character described comprising: a pair of generally parallel and opposed straps; a transverse arched member secured at either end to said straps for holding them in laterally spaced relation with respect to each other; strap extensions pivoted to the lower ends of said straps, the lower end of each of said extensions being provided with an elongated slot; a transverse bracket secured to and extending outwardly from the upper end of each of said extensions; and a spring loaded longitudinally extendable and adjustable heel bone pin carrier mounted on each of said brackets in parallelism with the extension on which said bracket is mounted.

2. A heel bone traction splint of the character described comprising: a pair of generally parallel and opposed straps held in laterally spaced relation with respect to each other by at least one arched connecting member, and arranged to be incorporated in a cast formed about a leg; a strap extension pivoted to the lower end of each of said straps; means for locking each of said extensions in any selected angular position with respect to

its associated strap; and a longitudinally extendable spring loaded heel bone pin carrier mounted on the exterior of each of said extensions and arranged for longitudinal movement in parallelism therewith.

3. A heel bone traction splint of the character described comprising: a pair of generally parallel straps secured together in laterally spaced relation with respect to each other by a transverse, arched and resilient connection member; a strap extension pivoted to the lower end of each of said straps and arranged to be locked thereto in any predetermined angular position, each of said extensions being formed with a transverse elongated slot for the accommodation of a heel bone pin; a bracket mounted on the upper end of each of said extensions and extending outwardly therefrom; a downwardly telescopic fitting mounted to each of said brackets in parallelism with its associated strap extensions; a coil spring surrounding each of said fittings and

arranged to urge its fitting to its extended position; a heel bone pin carrier mounted on the lower end of each of said fittings and arranged for longitudinal adjustment with respect thereto; and means for detachably securing said pin to each of said carriers.
